UNITED STATES PATENT OFFICE.

HARRISON D. STERRICK, OF PITTSBURGH, PENNSYLVANIA.

TELEPHONE ATTACHMENT.

1,367,169.

Specification of Letters Patent.

Patented Feb. 1, 1921.

Application filed July 10, 1919. Serial No. 309,930.

To all whom it may concern:

Be it known that I, HARRISON D. STERRICK, a resident of Pittsburgh, in the county of Allegheny and State of Pennsylvania, have invented a new and useful Improvement in Telephone Attachments, of which the following is a specification.

This invention relates to telephone desk sets. Its object is to provide a transmitting and receiving set in which the receiver is supported from the desk set in such position as to transmit the sound waves to the user's ear, thereby leaving both hands of the user free so that he can make memoranda, readily consult records, etc., while carrying on the conversation.

The invention can be embodied in a specially constructed desk set, but is also adaptable as an attachment which can be secured to standard desk sets, and which when so attached will securely hold the receiver and is so constructed that its center of gravity is fairly close to the center of gravity of the set itself so that the balance of the latter is not destroyed.

In the accompanying drawings Figure 1 is a vertical sectional view showing the invention applied as an attachment to a standard telephone desk set; Fig. 2 is a rear elevation of the same; Fig. 3 is a horizontal section through the stand immediately below the top collar thereon, and Fig. 4 is a fragmentary view partly in section showing one manner of adapting the invention as a permanent part of the telephone set.

In the drawings 1 indicates the stand or support of a form of desk telephone set in extensive use, the same having hinged to its upper end the usual microphone transmitter 40 and mouth piece 2. 3 indicates the usual hook for suspending the telephone receiver. The means illustrated for securing the invention as an attachment to a telephone stand, as shown in Figs. 1, 2 and 3, comprises a pair of bands 5 and 6 fastened around the stand 1, one above and the other below the usual collar 7 formed on said stand. The bands have their ends connected by suitable clamping means, such as compression bolts 8 passing through radial ears on the ends of said bands. Various other arrangements for securing the attachment to the stand will readily suggest themselves.

The band 5, at the rear of the stand 1, has formed thereon or secured thereto a disk or friction member 10. Another disk or fric-

tion member 11 is secured to the member 10 by any suitable pivoting means, such as the bolt 12, which serves also to adjust the frictional contact between the members 10 and 11, such as by means of the nut 13 on its end and the spring 14 interposed between said nut and the member 11. Secured to or formed integral with the member 11 is a horn 15 of such shape that when it is swung sideways to an inclined position its open end 16 will be in position to be contacted by the ear of the person who is speaking into the mouth piece 2. Within this horn is located the receiver 17 which may be (and for permanent constructions preferably will be) constructed especially for that purpose, but which, for attachments to existing sets will be the standard telephone receiver, and is so shown in Figs. 1, 2 and 3. This is inserted through an opening 18 in the back of the horn 15 and its upper end is held in contact with an internal shoulder 19 in the horn by means of a spring 20 in the base of the horn and bearing against the outer end of said receiver. 21 indicates the usual cord leading to the receiver.

Normally, that is when not in use, the horn will stand in vertical position, as shown in Fig. 2, projecting up behind and over the transmitter 2. When it is to be used, it is swung to one side or the other, until it is in such position that its open end 16 can be contacted by the ear of the user. It will remain in either position by reason of the frictional contact between the members 10 and 11.

In order that the movement of the horn may also serve to make and break the circuit, as is usual, the member 11 is provided with a projection 22 which is arranged to contact with a lever 23 which is pivoted at 24 to the band 6, and whose free end engages the telephone hook 3 at the point 25. The projection 22 is so located that when the horn 15 is in vertical position it presses downwardly on the lever 23, thus causing said lever to depress the telephone hook 3 to break the circuit, exactly as though the receiver 17 were hung on said hook; but when the horn 15 is swung to one side the projection 22 moves out of contact with the lever 23 thus permitting the telephone hook 3 to rise in the same manner as it does when the usual suspended receiver is removed therefrom.

The attachment described is of simple

construction, can be readily applied to an existing telephone set, does not materially disturb the balance of said set so that danger of upsetting is avoided, is easy of manipulation and enables the use of the telephone in a manner to leave both hands of the user free. The receiver 17 can be readily removed from the horn and used in the ordinary way if desired. The excess length of telephone cord 21 can be wound around the receiver, so that it does not hang down, thereby avoiding one source of possible upsetting of the telephone set.

Fig. 4 shows one manner in which the invention can be applied to a telephone set as a permanent part thereof. As here shown the disk 10^a is formed integral with the upper portion of the telephone stand, while the disk 11^a is pivoted thereto and held in frictional engagement therewith by the same means as are shown in Fig. 1. The member 11^a will carry the horn 15, which may be of the shape shown in Fig. 1 or otherwise formed so that when moved to one side its open end will be in position to be contacted by the ear of the user. In this case the receiver can and preferably will be specially constructed and permanently built in the horn. With such permanently built in receiver the usual hook 3 can obviously be modified and differently located, and, as shown, merely is a short pivoted arm 3^a projecting from the rear of the stand 1, in a position to be directly contacted by the projection 22 on member 11^a. Various other arrangements for embodying the invention as a permanent part of the telephone set will obviously occur to those skilled in the art.

Various modifications in the construction and arrangement of parts can obviously be made without departing from the invention as hereinafter claimed.

I claim:

1. In a telephone, in combination, a stand or support, a transmitter carried thereby, a horn pivotally connected to said stand to the rear of said transmitter and arranged to normally extend over said transmitter and to be swung to one side to bring its open end into position to be contacted by the ear of a person speaking into said transmitter, and a receiver associated with said horn.

2. In a telephone, in combination, a stand or support, a transmitter carried thereby, a

horn pivotally connected to said stand to 55 the rear of said transmitter and arranged to normally extend over said transmitter and to be swung to one side to bring its open end into position to be contacted by the ear of a person speaking into said transmitter, 60 a receiver associated with said horn, a cut out switch, and a projection on said horn arranged when the horn is in vertical position to depress said cut out switch and when the horn is in horizontal position to release said 65 cut out switch.

3. A telephone attachment comprising a support arranged to be attached to a telephone transmitter set, a horn arranged to contain and hold the receiver, a pivotal 70 connection between the horn and the support arranged to permit the horn to move from vertical inactive position to one side, and connections between the horn and the usual receiver cut out hook, said connection 75 including a cam so arranged that when the horn is in vertical position the cut out hook is depressed and when the horn is swung to either side said cut out hook is permitted to rise.

4. A telephone attachment comprising a support arranged to be secured to a telephone transmitter set, a horn formed to contain and hold the receiver, a pivotal connection between the horn and the support, a lever pivoted to the support and arranged to contact the cut out hook, and a projection movable with the horn and arranged when the horn is in vertical position to depress said lever and when the horn is 90 swung to either side to release said lever and permit the cut out hook to rise.

5. A telephone attachment comprising a support on a telephone transmitter set, a horn pivoted to said support to the rear of the transmitter, the free end of said horn curving forwardly, said horn being provided with an internal shoulder and with an opening through its wall permitting the receiver to be inserted therethrough, and 100 means for holding the receiver end against the internal shoulder of the horn.

In testimony whereof I have hereunto set my hand.

HARRISON D. STERRICK.
